Scott M. Abbott,

BY

J. Stuart Freeman,
ATTORNEY.

UNITED STATES PATENT OFFICE.

SCOTT M. ABBOTT, OF PHILADELPHIA, PENNSYLVANIA.

ADJUSTABLE BOOKMARK.

1,380,031.

Specification of Letters Patent. Patented May 31, 1921.

Application filed October 13, 1919. Serial No. 330,433.

To all whom it may concern:

Be it known that I, SCOTT M. ABBOTT, a citizen of the United States, residing at Philadelphia, in the county of Philadelphia 5 and State of Pennsylvania, have invented certain new and useful Improvements in Adjustable Bookmarks, of which the following is a specification.

The object of this invention is to provide 10 an improved book-mark, which will combine physical flexibility as well as flexibility, figuratively speaking, in its being so readily conformable to various types of books and ways in which the same are used.

15 More specifically, the invention has for its object the provision of a book-mark which is particularly designed for and adapted to be used with the Holy Bible, and such guides used in the study thereof as that work which 20 is known as *Christian Science and Health* used by Christian Scientists, wherein several correlated portions of the book are arranged in such manner, or that when read consecutively they form what might be termed a 25 more or less complete exposition of a particular subject.

A further object of the invention is to provide a book-mark comprising means removably attached to the opposite sides of 30 the binding, yielding means extending between the corresponding end portions of said first means, and removable elements yieldingly engaging and supported by said yielding means and adapted to be positioned between 35 the pages of a book, and said last-named means being provided with flexible arms hingedly connected thereto, and preferably extending to the laterally outer edge portion of the leaves of the book and supporting tabs, which may in turn be provided 40 with any desired numerals, letters, or the like.

With these and other objects in view, the invention comprises details of construction 45 and a method of operation hereinafter fully described when read in conjunction with the accompanying drawings, in which Figure 1 is a perspective view of a book, with which is associated the preferred embodiment of 50 the invention; Fig. 2 is a perspective view of the rear portion of a book so equipped; Fig. 3 is a side elevation of one of the elements adapted to be attached to the sides of the book-cover; Fig. 4 is a plan view of 55 one of the book-marking elements complete;

Fig. 5 is an enlarged detail perspective view of the free end portion of one of the flexible marker-arms, showing the method of attaching the numbered tabs thereto; and Fig. 6 is a fragmentary plan view of one end of a 60 modified form of marker element.

Referring to the drawings, a book is shown as comprising oppositely positioned side-boards 1 and 2, connected at their rear portions by an integral back 3, while between said boards are positioned the usual leaves 4. An elongated strip 5 of suitable material, and being provided at its opposite ends with laterally and reversely curved portions 6, is adapted to be slid longitudinally 70 from the outer free edge to the rearmost portion of each of the binding boards 2 of the book. These strips are furthermore provided upon their looped portions with pins 7, surrounding which are revolvably mounted pulley-wheels 8, while between the wheels, located at each end of the backing 3 of the book, a resilient member, such as a small rubber-band 9, is extended.

When a given portion of the book is to be 80 marked for instantly relocating the same, one of the marker units, shown in Figs. 4 and 5, is placed between the leaves, which latter upon separating exposes to the reader the portion in which he is interested.

85 These elements each comprise an elongated flexible strip 10 of very thin material, provided in their lower end portion with an inverted U-shaped recess 11 adapted to receive and partially surround one of the side portions of the lower of the rubber-bands 9. The upper end portion of said member is provided with an aperture 12, which preferably has one lateral edge 13 diagonally positioned, said last-named aperture being adapted to receive and partially surround one side portion of the upper of the rubber-bands 9, and by the arrangement of the apertured edge portion 13 to resist purely accidental dislodgment of the marker 90 from between the leaves of the book.

95 Each of the elements 10 is furthermore provided at a predetermined position between its end portions with an elongated aperture 14, through which extends, and is 105 reversely bent, one edge portion 15 of a hinge member, which has its opposite end portion provided with spaced parallel extensions 16 adapted to be bent laterally in the same direction as the portion 15, and re- 110

versely toward the same in order to coöperate with said other portion, to rigidly grip the marker member. Furthermore, between the spaced ears 16, there extends a relatively 5 fine pin 17, around which is slidably mounted a hinge member 18, to the free end portion of which is secured a preferably very thin flexible marker-arm 19, which extends laterally outwardly toward the free edge 10 portions of the leaves of the book when the marker as a whole is in normal operative position.

The faces of the outer end portion of each 15 marker-arm 19 are covered by a folded section of metal comprising oppositely positioned side portions 20 and 21. The side 21 is provided near its free end with oppositely positioned cut-out portions 22, and at its extreme end with laterally outwardly extending 20 tending arms 23, which are adapted to be bent in opposite directions and thence toward each other around the adjacent portion of the arm 19, while the side portion 25 20 of this folded member is provided at its end portion with oppositely extending ears 24, which are similarly bent in opposite directions and thence toward each other surrounding the adjacent portion of the arm 19, and terminating in the cut-out portions 30 22, and with their outer exposed surfaces flush with the corresponding surface of the side 21 of the said member. These tabs may be positively secured in their desired position by means of small rivets 25, or the like, 35 passing through the tab and the arm 19, and it is to be noted that the marker-arms are hingedly positioned upon the respective supporting members 10 of a series in such different consecutive positions as to make their 40 progress numerically from one end toward the other of the said members.

One or both of the sides 20 and 21 of the marker-arm or tab may be provided with numerals, letters, or other suitable indicia, 45 such for instance as that illustrated, for the purpose of indicating the sequence with which the portions of the reading-matter of a book are to be located. Also it has been found greatly to the advantage of the user 50 of such a marker to provide the looped portions 6 of each of the members 5 with bands 26 of any suitable material, which same operates to lessen the chance of the members 5 accidentally shifting with respect to the 55 book-covers, and also protects the surface of the table, desk, or the like, from being scratched by the exposed portions of the member 5 when a book equipped with the improved marker is laid or slid thereupon. 60 Also, referring to Fig. 6, there is shown a modification of the end portion of the members 10, which same comprises a recess 27 having a restricted opening 28 in one side portion of said member, instead of in

the end itself as is true with that form of 65 the device shown in Fig. 4.

What I claim and desire to protect by Letters Patent of the United States is:—

1. A book-marker, comprising the combination of members adapted to be attached 70 to the covers of a book, with a resilient readily flexible member extending between said first members, and a member removably supported by said resilient member and adapted to be positioned between the leaves 75 of a book.

2. A book-marker, comprising the combination of members adapted to be attached to the covers of a book, with a pair of rubber bands extending between said members, and 80 a member removably supported by and between said bands and adapted to be positioned between the leaves of a book.

3. A book-marker, comprising the combination of members adapted to be attached to 85 the covers of a book, with a pair of resilient members extending between said first members, and a member removably supported by and between said resilient members, and adapted to be positioned between the leaves 90 of a book.

4. A book-marker, comprising the combination of a pair of members adapted to be removably secured to the covers of a book, a pair of flexible members removably carried 95 by and between said first members, and a member removably supported by and between said flexible members, and adapted to be positioned between the leaves of a book, and the flexible members slidably engaging 100 said first members.

5. A book-marker, comprising the combination of a pair of members having folded portions adapted to secure the same to the covers of a book, a pulley-wheel carried by 105 each of the end portions of said members, an elastic member connecting the oppositely positioned wheels at each end of said members, and a flexible member removably supported by and between the said flexible 110 members.

6. A book-marker, comprising the combination of a pair of members having folded portions adapted to removably secure the same to the covers of a book, elastic members supported by and between the said first-named members, a member removably supported by and between the said elastic members, and a flexible arm extending laterally from said last-named member. 120

7. A book-marker, comprising the combination of a pair of members having folded portions adapted to removably secure the same to the covers of a book, elastic members supported by and between the said first-named members, a member removably supported by and between the said elastic members, a flexible arm extending laterally from 125

said last-named member, and a hinge connection between said arm and its supporting member.

8. In a book-marker, the combination of a member adapted to be inserted between the leaves of a book, a flexible arm laterally extending from said member, a hinge connection between said member and said arm, and a character-carrying member fixedly secured to the free end of said arm by bending oppositely positioned portions of said last member around the end of said arm, and bending extensions of said portions around the laterally opposite edges of said arm.

9. In a book-marker, the combination of a pair of members adapted to be secured to the covers of a book, an elastic member connecting said members, and a member adapted to be inserted between the leaves of a book and provided with a slot in the end to removably receive and engage said elastic member.

10. In a book-marker, the combination of a pair of members adapted to be secured to the covers of a book, a pair of elastic members connecting the end portions of said first members, and a member adapted to be inserted between the leaves of a book and provided in its ends with slots, adapted to removably engage the said elastic members, the inner end of one of said slots being closer than the outer end of the slot to one side of the slot-containing member.

11. A book-marker comprising the combination of members adapted to be attached to the covers of a book and movable independently of each other with the supporting portions of said covers, with a flexible member extending between said first members, and a member normally supported by said flexible member and adapted to be positioned between the leaves of a book.

In testimony whereof I have affixed my signature.

SCOTT M. ABBOTT.
